(57) **CLAIM**

The ornamental design for a bottle stoppering machine, as shown and described.

DESCRIPTION

FIG. 1 is a rear view, showing our new design;

FIG. 2 is a front view thereof;

FIG. 3 is a top view thereof;

FIG. 4 is a side perspective view;

FIG. 5 is a front perspective view thereof;

FIG. 6 is a side view thereof; and,

FIG. 7 is a rear perspective view thereof.

1 Claim, 7 Drawing Sheets(56)
